(57) **CLAIM**

The ornamental design for a size adjustable device to cover and secure implantable devices in surgical applications, as shown and described.

DESCRIPTION

FIG. 1 is a perspective view of a first embodiment of the size adjustable device to cover and secure implantable devices in surgical applications.

FIG. 2 is a top plan view of the size adjustable device to cover and secure implantable devices in surgical applications.

FIG. 3 is a bottom plan view thereof.

FIG. 4 is a front elevational view thereof.

FIG. 5 is a rear elevational view thereof.

FIG. 6 is a right side elevational view thereof.

FIG. 7 is a left side elevational view thereof.

FIG. 8 is a perspective view of a second embodiment of the size adjustable device to cover and secure implantable devices in surgical applications.

FIG. 9 is a top plan view of the second embodiment of the size adjustable device to cover and secure implantable devices in surgical applications.

FIG. 10 is a bottom plan view thereof.

FIG. 11 is a front elevational view thereof.

FIG. 12 is a rear elevational view thereof.

FIG. 13 is a right side elevational view thereof; and,

FIG. 14 is a left side elevational view thereof.
